EMBORESSED PLASTIC SHEET MATERIAL

Staley A. Carpenter, Marietta, Ohio, assignor to The B. F. Goodrich Company, New York, N.Y., a corporation of New York

Filed July 5, 1960, Ser. No. 61,220

Term of patent 14 years

(Cl. D87—3)

The figure is a plan view of an embossed plastic sheet material showing my new design.

The design unit is contained within the dot-and-dash lines, which unit is repeated in regular succession, as indicated by the extensions beyond the unit boundaries.

I claim:

The ornamental design for an embossed plastic sheet material as shown and described.
